A. WALTON.
STOPPER FOR OIL BARRELS.

No. 36,490.

Patented Sept. 16, 1862.

Inventor,

Henry Walton
Atty for A. Walton

UNITED STATES PATENT OFFICE.

ALLEN WALTON, OF PHILADELPHIA, PENNSYLVANIA.

IMPROVED BUNG FOR OIL-CASKS.

Specification forming part of Letters Patent No. 36,490, dated September 16, 1862.

To all whom it may concern:

Be it known that I, ALLEN WALTON, of Philadelphia, Pennsylvania, have invented a Metallic Stopper for Coal-Oil Casks; and I do hereby declare the following to be a full, clear, and exact description of the same, reference being had to the accompanying drawings, and to the letters of reference marked thereon.

My invention consists of a screw-tube and screw-plug with an intervening washer, the whole being constructed and applied to the stave of an oil-cask in the manner described hereinafter, so as to form a more secure stopper than an ordinary bung, and one which can be more readily removed and replaced.

In order to enable others to make my invention, I will now proceed to describe its construction and operation.

On reference to the accompanying drawings, which form a part of this specification, Figure 1 is a sectional view of my improved metallic stopper for oil-casks; Fig. 2, a face view of the stopper as it appears on the inside of the cask; Fig. 3, a sectional view of a modified form of the stopper, and Fig. 4 a face view of Fig. 1.

It is well known that great difficulty is experienced in keeping the bungs of coal-oil casks tight in their places, the agitation of the casks during transportation tending to loosen the bungs, owing to the latter as well as the holes in which they fit becoming impregnated with oil.

In casks for conveying coal-oil between distant localities it is usual to glue the bungs in their places to prevent them from being shaken loose, so that the withdrawal of the bungs is a matter of difficulty, and can rarely be effected without mutilating the cask. My improved metallic stopper has been designed with the view of remedying these difficulties.

On reference to Figs. 1 and 2, A represents a portion of the stave of the cask for containing coal-oil, and into this stave is bored a hole of sufficient diameter to freely admit the screw-tube B, the flange b, of which is let into a recess formed on the outside of the barrel, the tube being firmly secured to the stave by the nut a.

D is a metal plug, the head d of which has six, eight, or any other convenient number of sides, and on the body of the plug are three projections, e, the edges of which form inclined planes, the latter being arranged to

bear against projections f on the inside of the tube B.

m is a washer of leather, cork, or other material which will not be affected by the coal-oil, intervening between the head d of the plug and the flange b of the screw-tube B, so that when the plug is turned by a suitably-formed key and the inclined edges of the projections e bear against the projections f a perfectly-tight joint, effectually preventing the escape of the oil, is produced. On turning the plug in a contrary direction the inclined planes of the projections e will recede from the projections f, and the plug may be withdrawn when it has been turned to a given position—that is, when the spaces between the projections e coincide with the projections f.

In the modification illustrated in Figs. 3 and 4, the plug D, instead of being provided with inclined projections or portions of a screw, has the ordinary screw-threads adapted to similar threads in the screw-tube. With this exception, the stopper is precisely similar to that above described.

In order to add security to the plug, after it has been screwed tight, a key, n, may be driven between a projection, q, on the flange b of the screw-tube and one of the sides of the flange d of the plug, as best observed in Fig. 4, thereby preventing the latter from turning.

It will be seen without further description that, while my metallic stopper protrudes from the cask to no greater extent than an ordinary wooden bung, it is much more secure than the latter, and can be withdrawn and replaced with facility and without mutilating the cask.

I claim as my invention and desire to secure by Letters Patent—

In combination with the stave of a coal-oil cask, the screw-tube B, with its flange b, the screw-plug D and its head d, and the intervening washer, m, the whole being constructed and applied to the stave as set forth, for the purpose specified.

In testimony whereof I have signed my name to this specification in the presence of two subscribing witnesses.

ALLEN WALTON.
